UNITED STATES PATENT OFFICE

2,573,529

FRONT MOUNTED LAMP HOLDER

William R. Young, Fairfield, Conn., assignor to
General Electric Company, a corporation of
New York

Application June 18, 1948, Serial No. 33,877

4 Claims. (Cl. 173—339)

1

This invention relates to electrical lampholders and more particularly to lampholders adaptable for mounting on a flat surface made of thin material without direct access to the other side of the surface.

Lampholders used for this purpose ordinarily consist of two parts and require access to the back side of the surface in order that the part on the back side may be held in position while the lampholder on the front is properly secured.

Others employ the use of resilient springs which necessitate dependency upon the continued proper resilience of the springs and resistance to deformation and bending, and also are vulnerable to the entrance of foreign material between the resilient springs and the lampholder housing thus preventing return of the spring to its normal position for removal of the lampholder.

Still others require the making of an aperture in the surface sufficiently large to accommodate the body of the lampholder.

Finally, where the body of the lampholder protrudes behind the surface, such lampholder bodies must be treated as obstacles and wires on the back of the surface must be diverted around them in going from one point to another with a resultant increase in wiring cost. This increase in wiring cost becomes important where large numbers of lampholders are secured to a surface and is objectionable in other cases where space for wiring is at a premium.

It is one of the objects of this invention to provide a lampholder which can be easily mounted on an apertured surface made of thin material without a cooperating part on the other side of the surface and without the necessity of having an additional helper working behind the surface to tighten the usual mounting means.

A further object is to provide a rigid front mounting for a lampholder by use of non-resilient means.

Another object is to provide an easily mountable lampholder which will require only a small aperture for mounting and which will not extend back of the surface.

The above and other objects of the invention, as well as the manner of carrying out the same, will be apparent to those skilled in the art from a consideration of the accompanying drawing and following specification, wherein is disclosed a single exemplary embodiment of the invention with the understanding, however, that various changes may be made therein as fall within the scope of the appended claims.

In said drawing, Fig. 1 is a side elevation show-

ing the lampholder in position to be inserted in the aperture of the surface; Fig. 2 is similar to Fig. 1 except that the lampholder is mounted and secured to the surface; Fig. 3 is a rear elevation showing the lampholder secured in the surface as seen through the aperture in the surface; Fig. 4 is a front elevation of the lampholder; Fig. 5 is a partial section of the lampholder taken on line 5—5 of Fig. 4; Fig. 6 is a rear elevation with certain parts broken away; Fig. 7 is a limited partial section taken on line 5—5 of Fig. 4; and Fig. 8 is a partial disassembled perspective view.

In general, my invention comprises a lampholder which is anchored to a support by means of a mechanism having radially movable elements operable from the front of the lampholder.

Referring first to Figs. 4 and 5, the lampholder comprises a housing 2 which may be made of porcelain, molded plastics or other insulating material. Within this housing is a cylindrical recess 6 designed to house, for example, an Edison screw shell 7 and a center terminal 8 forming a lamp receptacle. The shell 7 is secured to the housing 2 by two screws 10 and 11. As shown in Figs. 6 and 8, screw 10 is secured by a nut 12 positioned in a recess 12' of housing 2, and serves to hold the shell 7 in place in the housing. Screw 11 is secured by a terminal plate 17 positioned in a recess 17'. Terminal screw 18 is threaded into terminal plate 17 and acts as a connector for one side of the line. Thus screw 11 serves to secure the shell 7 in position in the housing and also provides electrical connection between said shell and the terminal plate 17.

As shown in Figs. 4 and 5, center terminal 8 is shaped to conform with and rest upon projection 13 of housing 2. Said projection is perforated by a cylindrical passage 19 to accommodate a screw member 30 which will be more fully described later. The center terminal 8 has an opening 21 formed therein to admit a screw driver for movement of the screw member 30. It will be noted that a portion 15 of the base 14 and sidewall of the shell terminal 7 have been removed to accommodate the housing projection 13 and the center terminal 8. As shown in Fig. 5, a screw 9 secures center terminal 8 and threads into terminal plate 16 which rests in recess 16' of housing 2. Terminal plate 16 also has a screw 22 which acts as a line connector.

Means for securing the lampholder to the apertured surface is best shown in Fig. 8. The securing mechanism 3 is positioned in a recess 3' of housing 2 and comprises a frame 26, a screw member 30, and three bell crank lever members

32 each with angularly disposed arms 36 and 37. Said frame 26 may be made from a stamping having a base 38 perpendicular to the axis of said housing with a tapped center hole 27 therein, three sidewalls 33 radially disposed to the axis of said housing, and three ears 28 with perforations therein. The frame 26 is secured to the housing 2 by three screws 23, 24 and 25 passing through the three ears 28. The screw member 30 consists of a shaft with threaded portion 34, 10 screw head 20, two spaced shoulders 31 which may be parallel disks, and a smooth portion 35 of the shaft which may be of reduced cross section between the two spaced shoulders. Said screw member 30 threads into the tapped center hole 27. The three lever members 32 are secured and pivoted to the three sidewalls 33 of the frame 26 by three rivets 39 or other suitable means. The arm 36 of each lever member 32 is of such length and shape as to ride between the spaced shoulders 31 as the screw member 30 is threaded through the tapped center hole 27 in frame 26.

In the operation of this securing mechanism by turning the screw member 30 in one direction, it is threaded into the tapped hole 27 of the frame 26 whereby the screw member moves toward the back of the lampholder carrying the arms 36 of the lever members 32 with it and thus rotating said lever members about their pivots 39 causing the arms 37 to be radially displaced away from the axis of the housing as shown in Fig. 5. Conversely, when the screw member is turned in the opposite direction, it moves toward the front of the lampholder carrying the arms 36 of the lever members with it and causing the arms 37 to be radially displaced toward the axis of the housing as shown in Fig. 7.

Fig. 1 shows the lampholder 1 positioned before a surface 4 with an aperture 5 in said surface. Here the arms 37 are disposed toward the axis of the housing 2 and in this contracted position are ready for insertion in the aperture 5 of the surface 4.

Fig. 2 shows the lampholder positioned against the surface 4 with the arms 37 inserted in the aperture 5 and radially displaced away from the axis of the housing 2 so as positively and rigidly to engage the edge of the aperture 5 and hold the lampholder in mounted position.

The line wires 40 and 41 originate behind the surface and pass through the aperture 5 to be secured to or removed from the line terminals 18 and 22 from the front of the surface when the lampholder is removed from the surface.

It will be observed that my lampholder can be easily mounted on an apertured surface made of thin material without a cooperating part on the other side of the surface and without the necessity of having an additional helper working behind the surface to tighten the usual mounting means. It has a positive action and rigid members for attachment to the mounting surface. It will also be noted that the size of the lampholder will not be determined by the size of the aperture in the mounting surface, and that it is adaptable for mounting on surfaces having a considerable range of aperture dimensions. Moreover, my lampholder does not have parts of substantial size extending in back of the mounting surface to take up wiring space or provide objectionable obstacles to wiring.

Although the foregoing description is necessarily of a detailed character in order completely to set forth the invention, it is to be understood

that the specific terminology is not intended to be restrictive or confining, and it is to be further understood that various rearrangements of parts and modification of structural detail may be resorted to without departing from the scope or spirit of the invention herein claimed.

What I claim as new and desire to secure by Letters Patent of the United States is:

1. A lampholder adapted to mount against the face of an apertured surface comprising a lamp receptacle, a housing having a recess in the front thereof to accommodate said lamp receptacle and recesses in the rear to accommodate two line terminals, a frame secured in a rear recess of said housing and centered in said housing, said frame comprising a base perpendicular to the axis of said housing with a tapped hole in its center and a plurality of side walls radially disposed to the axis of said housing, a plurality of levers pivotally mounted on said walls and radially disposed to the axis of said housing, said levers projecting beyond the rear of said housing, a screw threaded into said tapped hole in the base of said frame in engagement with said levers for moving said levers radially toward and away from said axis for engagement and disengagement respectively of said levers from the aperture of said surface, said screw being accessible from the front of the lampholder through a passage between said front and rear recesses and a perforation in the center terminal of said lamp receptacle, whereby said lampholder may be secured to and disengaged from said apertured surface by operating said pivoted levers from the front of the surface.

2. A lampholder adapted to be mounted against the face of an apertured surface comprising a housing recessed at its front end, a lamp receptacle in said recess, a plurality of bell crank levers each having inner and outer angularly disposed arms, means for pivotally mounting said levers on the back end of said housing with said levers distributed in radial planes around the axis of said housing and with their inner arms adjacent to said axis and a screw accessible from the front end of the lampholder having a pair of spaced, outwardly extending, opposed shoulders to provide opposed bearing surfaces engaging the said inner arms of said levers for moving the same and thereby moving the outer arms of the levers into and out of engagement with the edge of the aperture of said surface for securing the lampholder thereto and releasing it therefrom.

3. A lampholder adapted to be mounted against the face of an apertured surface comprising a housing recessed at its front end, a lamp receptacle having a perforated center terminal centrally disposed in said recess, an axial passage in said housing extending from said recess to the back end of the housing, a plurality of bell crank levers each having inner and outer angularly disposed arms, means for pivotally mounting said levers on the back end of said housing with said levers distributed in radial planes around the axis of said housing and with their inner arms adjacent to said axis and a screw extending through said passage and accessible from the front of the lampholder through said apertured contact, said screw having opposed bearing surfaces engaging the said inner arms of said levers for moving the same and thereby moving the outer arms of the levers into and out of engagement with the edge of the aperture

of said surface for securing the lampholder thereto and releasing it therefrom.

4. A lampholder adapted to be mounted against the face of an apertured surface comprising a housing recessed at its front end, a lamp receptacle having a perforated center terminal centrally disposed in said recess, an axial passage in said housing extending from said recess to the back end of the housing, a plate mounted on the back of said housing and having a plurality of side walls extending therefrom disposed radially to the axis of said housing, a plurality of bell crank levers each having inner and outer angularly disposed arms, means pivotally mounting said levers on said side walls with said inner arms adjacent the axis of said housing, a screw extending through said passage and accessible through said apertured contact and being threaded into said plate, said screw having spaced shoulders engaging the ends of said inner

lever arms for moving the same and thereby moving said outer lever arms into and out of engagement with the edge of the aperture of said surface for securing the lampholder thereto and releasing it therefrom.
